UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR CASING OF SODA-WATER APPARATUS.

Specification forming part of Design No. 6,367, dated January 21, 1873.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

This invention consists in an ornamental design for the casing of a soda-water apparatus, to be placed against a wall, the operator standing in front of the apparatus.

In the photograph, A represents the lower portion of the casing of the apparatus, which is of oblong form. The central portion B rises vertically from the base a to the cornice b, while the portion C of the front on each side of the central portion B slopes or inclines inward and upward from c to the cornice b. This cornice is surmounted by an ornamental top, D, which stands out from the back E, which is provided with an ornamental top, and rises vertically from the base a. This back E is intended to be placed against the wall of the apartment,

the operator standing in front of the apparatus and between it and the counter. The central portions of the top D and cornice b project further from the back E than the portions on each side thereof, forming angles at d d, the design thus produced being unique and ornamental. On each side of the central portion B, and at each of the front corners of the apparatus, is a pillar, e, the outside pillars being provided with gas-burners, which may, however, be dispensed with, if desired.

Claim.

What I claim as my invention, and desire to secure by Letters Patent, is—

The design for the casing of the soda-water apparatus, substantially as herein shown and described.

Witness my hand this 6th day of January, A. D. 1873.

GEO. F. MEACHAM.

In presence of—

P. E. TESCHEMACHER,
G. A. MEACHAM.
